CLAIM

The ornamental design for an integral ductwork takeoff, as shown and described.

DESCRIPTION

FIG. 1 is a perspective view thereof;

FIG. 2 is a side view thereof as taken from the right side in FIG. 1;

FIG. 3 is a side view thereof as taken from the left side in FIG. 1;

FIG. 4 is a rear view thereof as taken from the right side of FIG. 2;

FIG. 5 is a front end view thereof as taken from the left side in FIG. 2;

FIG. 6 is a top view thereof; and,

FIG. 7 is a bottom view thereof.
